UNITED STATES PATENT OFFICE.

AMOS LEA KELTNER, OF TULSA, OKLAHOMA, ASSIGNOR TO WALKER S. ESTES, OF TULSA, OKLAHOMA.

DERRICK.

Application filed January 19, 1924. Serial No. 687,304.

To all whom it may concern:

Be it known that I, AMOS LEA KELTNER, a citizen of the United States, and resident of Tulsa, in the county of Tulsa and State of Oklahoma, have invented certain new and useful Improvements in Derricks, of which the following is a specification.

The invention relates to a derrick of the type generally employed in drilling oil wells and the like work, and is intended to eliminate the racking from heavy strains which ordinarily come upon the truss work of the ordinary derrick when heavy loads are applied or when one of the leg members yields, either through compression or because of failing of the foundation thereof.

An object of the invention is to provide a derrick in which the truss work is mounted on individual foundations, and the leg members proper have no positive connection with the corner brackets of the truss work.

Another object of the invention is to provide a derrick which can be readily assembled with the use of but few fastening members, and in which any girt can be easily removed for replacement in case one becomes broken or bent.

Other objects will be apparent from the following detailed description and the appended claims.

In the drawings:

Figure 1 is a side view of the completed derrick.

Figure 2 is a view of one form of the corner brackets used except at top and bottom of the truss.

Figure 3 is a view of another form of corner bracket used at the bottom of the truss.

Figure 4 is a view of one end of one of the girts.

Figure 5 is a view showing the manner of fastening together the sections of the wooden legs.

Figure 6 is a side view, partly in section, showing the manner of assembly of the derrick.

Figure 7 is a view of the top of the derrick showing how one of the legs can yield without distortion of the frame of the derrick.

Figure 8 is a view of a modified form of truss work.

The base portion of the truss work is composed of posts 1 which rest on individual foundation bearings 2 and support an upper

cross bar 3. The posts are connected by a lower cross bar 4 and braces 5 and 6 connect the members mentioned. The braces 5 are connected to the posts 1, the braces 6 to the upper bar 3, also the braces 6 are connected to the middle of the lower bar 4, to the braces 5, to the posts 1 and to the outer ends of the upper bar 3 where it is connected to the lowermost set of corner brackets 7. These lower corner brackets, as shown in Figure 3, have a flat portion 8 to which the bar 3 is attached by bolts passing through openings 9, an opening 10^a for the turnbuckle rod and a socket 11 on the adjacent side to receive the ends of the girts 12. These girts are formed at their ends with tapered portions 13 which drop readily into the sockets 11 but cannot pass therethrough. Any girt can be readily removed and replaced when broken without disturbing any other portion of the structure.

All of the intermediate corner brackets 14, shown in Figure 2, have two sockets 11 for the girts just described, and openings 10^a for the ends of the turnbuckle rods. These girts may be made of wood, channel iron or T-beam, but in all cases have the tapered end portion. The girts are held in position by rods or pipes 15 which fit at their ends into sockets 10 in the corner brackets and by thus spacing apart the corner brackets position the girts.

Rods 16 provided with turnbuckles 17 hook at their ends into the openings 10^a in the corner brackets as illustrated; the rods 90 of each pair crossing each other. The upper corner brackets 18 as shown in Figure 1 are of slightly different shape. These brackets are longer on the outside and the extended portion is inclined slightly outward. They are also beveled from the outside to the inner part and have no sockets 11 at the top nor openings for attachment of upper turnbuckles. A truss structure of the type described can be built up in section 100 without the use of any bolts or similar fastening means, and when assembled can be given a high degree of firmness by properly tightening the turn buckles.

It is not uncommon to provide with such a derrick structure corner legs, but these have generally been rigidly fastened to the structure of the truss in such manner that any yielding of the legs would result in strain on the truss structure. It is an ob- 110

ject of the present invention to avoid any such objectionable result. The legs of the present device are built up preferably of wooden sections 19 held together by dowel pins 20. These sections pass through openings 21 in all of the corner brackets 7, 14 and 18 and extend some distance above the top of the truss work. These openings 21 are shown as square, but the precise form 10 is immaterial. Three legs have sections 22 that extend below the bar 3 of the truss structure and rest upon independent foundations 23. The upper ends extend above the brackets 18 and have crown blocks 24 resting upon short header portions 25.

It is to be noted that there is no positive connection whatever between the legs and the corner brackets or any other part of the truss structure. If any excessive weight, 20 or yielding of one of the foundation members 23 causes one of the legs to drop, as indicated by dotted lines in Figure 7, this produces no distortion whatever of the truss structure which is unaffected by this movement. The derrick will therefore have a sufficient amount of flexibility to meet all conditions without producing any distortion of the truss work or bringing breaking strain thereupon. The engagement between the members 18, 24 and 25 is sufficiently loose to allow the yielding movement referred to. This is true even if the individual foundation be omitted as in the case of using wooden reinforcing legs for 30 the purpose of converting a steel pumping derrick into a drilling derrick.

As shown in Figure 8, the same principle may be also applied to a derrick constructed of ordinary angle iron 26. In this case a 40 special form of bracket 27 is employed at the corners, having an opening 28 to fit the wooden legs 19, and two integral right angle arms 29 bolted or similarly fastened to the sides of the angle iron 26. The bracket also 45 has an eye 30 to engage a turnbuckle rod if desired to keep legs from twisting. This construction has all the advantages of the other, since there is no positive connection between the wooden legs and the metal 50 framework of the derrick.

It is obvious that the same principle may be applied to other forms of derricks, and that certain details may be used without

others or with different forms of other elements.

55

I claim as my invention:—

1. A derrick comprising a frame work, reinforcing legs associated with the frame work but freely movable relative thereto, and separate foundations for the frame work 60 and reinforcing legs.

2. If a derrick comprising a frame work, including supporting legs, reinforcing legs associated with the frame work but freely movable relative thereto, and a separate 65 foundation for each of said legs, whereby settling of any of the reinforcing leg foundations may occur without distorting or straining the frame work.

3. A derrick comprising corner brackets 70 spaced apart lengthwise of the derrick by rods or pipes and having tapered openings therein, girts having tapered ends fitting within said openings, rods provided with turnbuckles connecting the corner brackets, 75 said brackets provided with openings, and sectional legs passing through the openings in said brackets and resting upon individual foundation members, said legs and brackets being capable of independent movement. 80

4. A derrick comprising corner brackets separated by frame members of the truss work and provided with openings, sectional legs passing through said openings and independently movable relatively to the 85 brackets, foundation members for the truss work, and individual foundation members for the legs.

5. A derrick comprising a frame work 90 having corner brackets provided with openings, sectional legs passing through said openings and movable relatively to the brackets or frame work, foundation members for the frame work, and separate foundation members for the legs. 95

6. A derrick comprising a frame work having corner brackets provided with openings, legs matching said openings and passing through them but which may move entirely independent of the frame work, and foundation members upon which the frame work and legs rest independently. 100

In testimony whereof, I have hereunto subscribed my name.

AMOS LEA KELTNER.
